UNITED STATES PATENT OFFICE.

JAMES CAVANAGH, OF BOSTON, MASSACHUSETTS, ASSIGNOR TO UNITED SHOE MACHINERY COMPANY, OF PATERSON, NEW JERSEY, A CORPORATION OF NEW JERSEY.

MANUFACTURE OF SHOES.

1,106,780.

Specification of Letters Patent. Patented Aug. 11, 1914.

Application filed August 31, 1910. Serial No. 579,814.

To all whom it may concern:

Be it known that I, JAMES CAVANAGH, a citizen of the United States, residing at Boston, in the county of Suffolk and State 5 of Massachusetts, have invented certain Improvements in the Manufacture of Shoes, of which the following description, in connection with the accompanying drawings, is a specification, like reference characters on 10 the drawings indicating like parts in the several figures.

This invention relates to the manufacture of boots and shoes and particularly to lasting shoes. It was the practice formerly in 15 making welt shoes to secure the upper in over-worked position by tacks driven through it into the innersole about the sides and the toe end of the shoe. It was found necessary to drive the tacks close together about the 20 toe to hold that portion of the upper. These closely placed tacks about the toe cut up the upper and the innersole badly and the tacks constituted such a serious obstruction to the 25 welt sewing-on or weltting operation that the lasting tacks had to be pulled out when 30 the upper had somewhat set in its stretched condition and a smaller number of more slender "stay" tacks provided in their places. These, however, are objectionable 35 only in less degree, for the same reasons, as the lasting tacks. To reduce these difficulties it has become the practice to tack the sides of the shoe and bind in the toe with a wire. It has also been proposed to sew the 40 upper to the lip of the innersole around the shoe but this cuts up the upper and the innersole lip at the toe, particularly in narrow toed shoes, so as greatly to weaken the material that must hold the inseam or welt 45 attaching seam. In accordance with the present invention which involves a novel method of securing the upper in lasted position these difficulties are obviated.

In its broadest aspect this invention consists in securing an upper in lasted position at a plurality of separate points along the sides of the shoe and binding in the toe portion of the upper with a continuous fastener. This fastener may advantageously be a 50 thread with which stitches may be made along the side of the shoe and which will constitute a suitable binder to tie in the toe portion of the upper against the lip of the innersole. Among the advantages which 55 will be apparent for the use of this method

is the fact that the securing of the upper along the sides and around the toe of the shoe constitutes a single continuous operation. It can be done uninterruptedly with a single tool or set of tools and a single fastening material thus simplifying and expediting the operation. By this method no obstruction is applied to the shoe which will delay the weltting operation or cause breakage of sewing needles. There are no lasting 60 tacks or wires to remove from the shoe preparatory to or after the weltting operation and no liability that a tack or a portion of a tack stem will be left in the shoe to dull the inseam trimmer or to work into 65 the wearer's foot. A very important advantage over sewing all around the shoe as heretofore suggested is that the upper and the lip are not mutilated and weakened around the toe as is necessary in such sewing 70 operation.

The invention will be more fully explained in the following description, reference being had to the accompanying drawing in which is shown one form of apparatus by the aid of which the invention 75 may be practised.

Figure 1 is a perspective view of a portion of a lasting machine in which a shoe appears with the upper overworked and held in position to be secured, together with a sewing tool being used to form a stitch for securing the rear portion of the upper on one side of the shoe. Fig. 2 illustrates the work on a larger scale, showing the 80 loops extending through the upper and the innersole lip, the needle with which the loops are inserted, and the locking strand which extends through the loops. To avoid confusion in the lines of the drawings the 85 fastening is shown as loosely applied, where-as it will be understood that in practice the loops may be drawn snugly. Fig. 3 shows a shoe, the upper of which has been secured in accordance with this invention by a series of stitches at the sides of the shoe and a binder at the toe, said stitches and binder being all formed from a continuous strand of fastening material. Fig. 4 is a detail.

The toe and heel lasting means of the 90 drawings comprise wiper plates 2 and 4 of well known type having continuous edges to embrace and work over the last, or the innersole thereon, the upper material of an entire end portion of the shoe at once. At 95

the heel the marginal portion of the upper is laid down upon the innersole and secured by tacks which may be clenched on the usual heel plate of the last and constitute permanent fastenings. About the toe and also along the sides of a welt shoe the upper is first to be temporarily secured and then permanently connected to the lip of the innersole by the inseam formed by the welter in sewing the welt to the lasted shoe. The toe wiper plates therefore lay the upper over the feather of the innersole and against the upstanding face of the lip. The side lasting devices are a series of pincers 5 shown as four on each side of the shoe, which operate to pull the upper over the last bottom and hold it under tension until it is secured. The pincers may be of well known construction, such for example as shown in 10 Chase Patent No. 478,501. The stitch forming apparatus is illustrated as a hand sewing tool 6 having a curved needle 8 adapted to carry a loop through the upper and the lip of the innersole.

15 In practising the invention a loop 10 is passed by the needle through the upper and the lip of the innersole at the point where the upper should be secured for holding it in lasted position. This loop may be passed 20 through the upper adjacent to the pincer or elsewhere at such a distance from the lip as will cause the stitch to tighten or draw the upper into desired snug relation to the lip. Alternatively the loop may be passed from 25 the innerside outwardly through the lip first and then through the upper. The free end portion 12 of the strand of the fastening material will be long enough to reach around the shoe to lock the loops. Alternatively a separate strand of the same or of 30 different fastening material may be used to lock the loops. The needle is preferably advanced through the layers of stock to be united far enough to permit a partial retraction to open the loop. This having been 35 done, the end portion of the strand is passed through the loop and the loop is tightened to form a type of lock stitch of well known characteristics. Another loop is then similarly passed through the upper and lip at 40 the next point where securing is desired and the operation repeated from the rear of the shoe until the toe is reached. Each stitch, as herein described, locks or anchors the fastening material but a different form of stitch 45 might be used in which special manipulation would be given to lock the fastening material at the first stitch and to anchor it at the stitches next the toe. The fastening material, and it may be either or both strands 50 and in the latter case they may or may not be twisted into a unit, is then passed around the toe portion of the upper which has been shaped by the wiper edges against the upstanding lip of the innersole to form a seat 55 for the binder. The wipers may be partially backed off the work, as is usual for this purpose. The fastening material is tightened to bind the upper externally to the lip and may be temporarily held tight 60 by advancing the wipers again; or the binder may be tightened as a part of the operation of tightening the first stitch on the second side of the shoe. This first loop, when tightened in forming the stitch, anchors the second end of the binder, the first end of which was anchored by the last stitch formed on the first side of the shoe, as in fact it was by each stitch on that side of the shoe. Stitches are now made at such other points along the ball and shank of the second side of the shoe as are required for holding the upper to the lip. These stitches may advantageously be located close to the pincer pulling points and may be on either or both 65 sides of such points. The pincers may be released progressively as the stitching progresses if suitably arranged for that purpose or they may all be released together after the securing operation is completed. 70 The wipers will also be backed completely off the shoe at a suitable time and the shoe removed from the machine. It will be observed that by this invention I apply an outside binder to the lasted shoe from the shank 75 on one side to the toe, then around the toe and back to the shank on the second side of the shoe. I anchor this binder not only at its ends but at such points intermediate the ends and the toe as require attachment 80 to the shoe in order to cause the portion of the binder between the points of attachment to hold the upper against the innersole in position to be sewed by the welt attaching machine. The section of the binder 85 which extends around the toe of the shoe is entirely external or outside the upper and is maintained in binding position by the tension upon it and by the shape of the toe. In so considering the outside strand as such 90 a binder extending around the shoe from shank to shank it is immaterial whether the outside strand is the loop containing strand as in Fig. 2 or is the locking strand or portion of the strand as in Fig. 4.

Having set forth the nature of this invention and explained how it may be used I desire to secure by Letters Patent of the United States protection for all the patentable novelty herein disclosed and I particularly claim the following:

1. The method of making shoes which consists in working an upper over a last, and securing the upper to the innersole lip at intervals along the sides of the shoe from 100 the shank forwardly and binding the upper to the lip about the toe portion of the shoe all with a continuous strand.

2. The method of making shoes which consists in working an upper over a last, 105

stitching the upper to the lip of the inner-
sole along one side of the shoe from the
shank forwardly to the ball, then binding
the upper to the lip about the toe and then
5 stitching the upper to the lip on the second
side of the shoe rearwardly to the shank.

3. The method of making shoes which
consists in working an upper over a last
at a plurality of points along the sides of

10 the shoe and in a continuous line around the
toe, anchoring a strand at the rear of one
side, fastening the upper to the lip of the
innersole by the strand adjacent to each over-
working point along that side, binding the
15 upper externally to the lip by said strand
around the toe, fastening the upper by the
strand adjacent to the overworking points
along the second side, and anchoring the
end of the strand.

20 4. The method of making shoes which
consists in working an upper over a last,
anchoring a strand at the rear of one side,
securing the upper by stitches along that
side to the toe, anchoring the strand, bind-
25 ing the upper entirely externally to the lip
of the innersole around the toe, anchoring
the binder, stitching the second side of the
shoe, and anchoring the strand at the rear
of the second side.

30 5. The method of making shoes which
consists in working an upper over a last,
passing a loop of a strand through the up-
per and the lip of the innersole, and an-
choring the loop at intervals along one
35 side of the shoe from the rear toward the
toe, externally binding the toe portion of
the upper to the lip by the strand, and then
securing the upper on the second side of
the shoe from the toe rearwardly at inter-
40 vals in the same manner as the first side has
been secured.

6. The method of making shoes which
consists in working an upper over a last,
passing a loop of a strand through the up-
45 per and the lip of the innersole, locking the
loop with one end portion of the strand, re-
peating this operation at intervals from the
rear toward the toe to secure one side of
the upper, binding the toe portion of the
50 upper externally to the lip of the inner-
sole, and securing the second side from the
toe rearwardly by loops locked with the end
portion of the strand.

7. The method of making shoes which
55 consists in working an upper over a last,
stitching the upper to the lip along one side
from the rear forwardly with a double
thread, binding the upper externally to the
lip by the two thread strands, and then
60 stitching the upper to the lip along the sec-
ond side of the shoe from the toe rear-
wardly.

8. The method of making shoes which
consists in working an upper over a last,
65 stitching the upper to the innersole from

the rear toward the toe and anchoring the
stitching material, making a binder of the
stitching material and securing the upper
externally about the toe therewith, anchor-
ing said binder, and stitching the upper 70
rearwardly along the opposite side of the
shoe.

9. That improvement in method of mak-
ing welt shoes which consists in temporarily
securing the uppers in lasted position along 75
the sides and around the toe by a continu-
ous fastener which is anchored at a plu-
rality of points along one side, then extends
as a binder wholly externally around the
toe and is anchored at intervals along the 80
ball and shank of the second side.

10. That improvement in method of mak-
ing welt shoes which consists in working the
upper over a last and applying a continuous
binder from the shank on one side around 85
the toe to the shank on the other side by an-
choring the binder to the upper and the in-
nersole at points along the sides of the shoe
required for causing it to confine the upper
in position to be sewed to the innersole lip 90
and extending the middle portion of the
binder under tension entirely externally
around the toe portion of the shoe.

11. The method of making shoes which
consists in working an upper over a last at 95
a plurality of points along the sides of the
shoe and in a continuous line around the
toe, holding the upper temporarily in over-
worked position, inserting a series of
stitches through the upper and lip of the 100
innersole to secure the upper in position for
the final inseam sewing operation, and re-
leasing the upper from the temporary hold-
ing means progressively as the stitches are
105 inserted.

12. The method of making shoes which
consists in working an upper over a last at
a plurality of points along the sides of the
shoe and in a continuous line around the
toe, holding the upper temporarily in over-
110 worked position, inserting a series of
stitches at the sides of the shoe through the
upper and lip of the innersole to secure
these parts together, binding the upper ex-
ternally to the lip by a strand of the stitch 115
forming material around the toe, and releas-
ing the upper progressively from its tem-
porary holding means during the upper se-
curing and binding operations.

13. The method of making shoes which 120
comprises inserting a thread fastener
through the upper and lip of the innersole,
passing a length of thread from the fas-
tener about the toe of the shoe, and insert-
ing a second fastener at the opposite side 125
of the toe to anchor the toe thread in place
and bind in the toe portion of the upper.

14. The method of making shoes which
comprises passing a thread from the outside
of the shoe through the upper and lip of 130

the innersole at one side of the toe to form a stitch, carrying the thread around the outside of the toe and forming a second stitch from the supply thread upon the opposite side of the toe to anchor the toe thread and bind in the toe portion of the upper.

In testimony whereof I have signed my name to this specification in the presence of two subscribing witnesses.

JAMES CAVANAGH.
